UNITED STATES PATENT OFFICE.

CONRAD WERRA, OF WAUKESHA, WISCONSIN.

METHOD OF CONSTRUCTING PISTONS.

1,195,306.

Specification of Letters Patent. Patented Aug. 22, 1916.

Original application filed June 18, 1914, Serial No. 845,774. Divided and this application filed September 25, 1914. Serial No. 863,482.

To all whom it may concern:

Be it known that I, CONRAD WERRA, a citizen of the United States, and resident of Waukesha, in the county of Waukesha and 5 State of Wisconsin, have invented new and useful Improvements in Methods of Constructing Pistons, of which the following is a description, reference being had to the accompanying drawings, which are a part 10 of this specification.

This invention relates to improvements in the method of constructing pistons, the present application being a division of my application on piston construction, Serial No. 15 845,774, filed June 18th, 1914.

In the manufacture of internal combustion engines the tendency is toward light-weight high speed engines. In engines of this type the cylinders and pistons are 20 usually formed of iron and are therefore comparatively heavy and considerable power is lost in overcoming inertia of movement of the heavy piston at the end of each reciprocation.

25 A further objection to pistons formed of iron or like material is that the weight causes unnecessary vibration which increases the wear on the parts and thereby consumes additional power.

30 It is one of the objects of the present invention to overcome the before mentioned objectional features and provide a method of constructing pistons whereby pistons may be formed which are of less weight than the 35 pistons now in use, and in which provision is made for taking the wear of the parts thereof.

40 A further object of the invention is to provide a method of constructing pistons whereby the major portion of the piston may be formed of aluminum or other light weight metal protected with other metal at points subjected to greatest wear.

45 A further object of this invention is to provide a method of constructing pistons in which parts are adapted to conform to the irregularities in shape of the inner wall of the cylinder of the engine of which the piston forms a part.

50 A further object of the invention is to

provide a method of constructing pistons of two metals of different degrees of coefficient of expansion whereby provision is made for permitting the unequal expansion of metals while the piston is in use.

55

With the above and other objects in view the invention consists in the improved method of constructing pistons as set forth in the claims.

In the accompanying drawing in which 60 the same reference characters indicate the same parts in all of the views, Figure 1 is a sectional view of a portion of a mold illustrating the method of forming the piston of a plurality of different metals, the bearing 65 rings being shown in position before casting the body portion therearound; Fig. 2 is a longitudinal sectional view of the completed piston; Fig. 3 is a transverse sectional view thereof taken on line 3-3 of Fig. 2; and 70 Fig. 4 is a side view of the complete piston.

Referring to the drawing numeral 5 indicates the body portion of the shell of the piston which is formed of aluminum or other light weight metal, and is provided 75 with the usual inwardly extending bored bosses 6 to receive the cross pin to which the connecting rod is pivotally mounted. The bosses are reinforced by ribs 7 which extend upwardly and connect with the top or end 80 wall 8 of the piston. One of the bosses is provided with a threaded opening 9 to receive a set screw for clamping the connecting rod cross pin in position. This end wall is of convex form to better resist the strain of 85 the explosion. The piston is cast partly around unbroken bearing rings 10 and 11 preferably of iron which are of slightly larger diameter than the piston in order to engage the surface of the bore of the cylinder. The rings 10 are of rectangular form in cross section and fit snugly in the grooves 12 formed in casting the piston.

The inner upper portion of the bearing ring 11 is also of substantially rectangular 95 form in cross section with a flanged bearing portion 13 extending toward the open end of the piston. The ring also fits snugly within a groove 14 formed in casting the piston. The ring 11 is provided with annu- 100

lar grooves 15 to receive split piston packing rings of ordinary construction.

In casting the pistons, the rings are cut to size and shape and are then placed in their

- 5 respective positions in a die or sand mold 16 as indicated in Fig. 1 and the molten aluminum or other light weight metal is then poured into the casting space 17 formed in the mold and in filling the space the metal 10 will engage the exposed inner and portions of the upper and lower surfaces of the bearing rings 10 and 11.

As the coefficient of expansion of aluminum is greater than iron the aluminum in 15 cooling in the mold will contract and draw away from the inner surfaces of the bearing rings and form annular spaces 18 as shown in Figs. 2 and 3 which will permit the expansion of the piston when doing its 20 work within the cylinder without unduly straining the packing rings.

It is a known fact that the cylinder bores of the engines become distorted and out of true after being bored and polished due to 25 the varying thicknesses of the metal forming the walls of the cylinders and consequently when the pistons are mounted within the cylinders they will only engage portions of the cylinder walls. The annular expansion spaces 18 permit the bearing rings 30 to yield slightly and conform to the irregularities of the cylinder walls and thus eliminate undue friction and wear.

The light weight of the piston due to the 35 major portion of the metal being aluminum requires less power to reciprocate it back and forth and vibration is therefore reduced to the minimum.

From the foregoing description it will be 40 seen that the method of constructing pistons provides a light weight piston adapted for the purpose described and which possesses the necessary strength to withstand the wear it is subject to.

45 What I claim as my invention is:

1. A method of constructing pistons of two metals of different degrees of coefficient of expansion, consisting of finishing the portion of lesser expansibility and casting a 50 portion of greater expansibility within the portion of lesser expansibility and in engagement therewith and permitting the contraction of the cooling cast metal to withdraw radially therefrom to provide spaces 55 for the expansion of said portion of greater expansibility.

2. A method of constructing pistons of two metals of different degrees of coefficient of expansion, consisting of finishing a bearing ring of lesser expansibility and casting a piston shell of metal of greater expansibility within the ring and in engagement with the inner and portions of the edge surfaces of said ring and permitting the con-

traction of the cooling shell to withdraw 65 radially from the inner surface of the ring to provide a space for permitting the expansion of the shell.

3. A method of constructing pistons of two metals of different degrees of coefficient 70 of expansion, consisting of placing a plurality of unbroken bearing rings of lesser expansibility in spaced relation within a mold and casting a piston shell of metal of greater expansibility within the rings and 75 in engagement with the inner and portions of the edge surfaces of said rings and permitting the contraction of the cooling shell to withdraw radially from the inner surface of the rings to provide spaces be- 80 tween the inner peripheries of the rings and the shell for permitting radial expansion of the shell.

4. A method of constructing pistons of two metals of different degrees of coefficient 85 of expansion, consisting of placing a plurality of unbroken bearing rings of lesser expansibility in spaced relation within a mold and casting a piston shell of metal of greater expansibility within the rings and 90 in engagement with the inner and portions of the edge surfaces of said rings and permitting the contraction of the cooling shell to withdraw radially from the inner surface of the rings to provide spaces between 95 the inner peripheries of the rings and the shell for permitting radial expansion of the shell, said bearing rings having approximately parallel edge faces which are engaged by portions of the shell and one of 100 the said rings having an annular recess for receiving a split packing ring.

5. A method of constructing pistons of dissimilar metals, which consists in placing bearing rings in a mold, then pouring a 105 dissimilar molten metal into the mold to form a piston shell which partly surrounds the bearing rings and non-adherently holds them in position, the metal of the piston shell having a greater coefficient of expansion than the rings and withdrawing radially therefrom in cooling to provide space to permit of the greater expansibility of 110 said piston shell.

6. A method of constructing pistons of 115 dissimilar metals, which consists in placing iron bearing rings in a mold, then pouring aluminum in a molten state into the mold to form a piston shell which partly surrounds the bearing rings and non-adherently holds 120 them in position, the metal of the piston shell having a greater coefficient of expansion than the rings and withdrawing therefrom radially to provide space to permit of the greater expansibility of said shell.

7. A method of constructing pistons of dissimilar metals, which consists in placing iron bearing rings in a mold, one of said

rings having an annular groove for receiving a packing ring, then pouring aluminum in a molten state into the mold to form a piston shell which partly surrounds the bearing rings and non-adherently holds them in position, the metal of the aluminum shell having a greater coefficient of expansion than the iron of the bearing rings and withdrawing radially therefrom to provide

space to permit of the greater expansibility of said piston shell metal.

In testimony whereof, I affix my signature, in presence of two witnesses.

CONRAD WERRA.
